UNITED STATES PATENT OFFICE

2,549,772

SHEET METAL FEED DEVICE

Frank V. Carroll, Munster-Hammond, Ind., assignor to Inland Steel Company, Chicago, Ill., a corporation of Delaware

Application June 18, 1945, Serial No. 600,092

2 Claims. (Cl. 214—1)

1

This invention relates to a sheet metal feed device, and more particularly to a very simple and effective means for feeding tin plates and the like to a stacker so that alternate sheets will have their list edges at opposite sides of the pile.

As is well known, any metal sheet which has been coated with a hot dipped metal, such as tin, acquires a thickening at the list or drip edge thereof due to an accumulation of metal at that edge as the sheet is lifted from the molten metal bath. This thickness is such that if the metal is stacked with the list edges of the sheets all at one side of the stack or pile, that side will be very much thicker than the other. In practice heretofore the sheets have been stacked with all of the list edges on one side, after which they are divided by hand labor, usually a certain number of sheets being counted off and turned 180° in a horizontal plane, after which an equal number of the sheets is added without turning so that when the stack is complete the edge portions are of even height, with the center of the stack lower than either side. This is an expensive and cumbersome operation, and the present invention eliminates all need for it by turning alternate sheets as they emerge from the plating bath.

The invention is illustrated in the drawings in which,

Fig. 1 is a side elevation partly in section of a plating bath of the usual type and having a feeding device applied at the top thereof the feeding device which is the basis for this invention;

Fig. 2 is a side view of the alternator.

In accordance with the invention, the sheets 10 are fed seriatim through the bath of molten metal 11 in any conventional manner. They are then fed upwardly by rolls 12 through the bath of palm oil 13 between the guides 14 and the rolls 15. In conventional operation, the sheets at this stage are directed by a guide such as the cone 16 onto the slide 17 from which they pass to a conveyor and are drawn through the bath 18 to a conventional stacking apparatus. In the present structure, however, the sheets come into contact with one surface of the alternator 20 which is provided with two concave cam surfaces 21 and 22 which converge in the elongated point 23. This alternator is pivotally mounted as on a pin 25 in the cone 16 and may rock from one position, shown in Fig. 1, to the other, its position being limited by the pins 26 and 27 which engage the sides of the cone 16 at their respective limits of position.

Assuming that the alternator is in the position

shown in solid lines in Fig. 1 a sheet emerging from the rolls 15 contacts the surface 21 at a point near the bottom thereof. As the sheet rises it rocks the alternator toward the position shown in dotted lines. As it does so the sheet bends toward the right, while the point 23 is brought toward or near the back of the sheet. In some cases the point will actually move the sheet somewhat toward the right. As the sheet rises the weight of metal above the cam surface 21 gradually increases and, therefore, changes the curvature of the sheet and this permits the alternator to gradually reach the position shown in dotted lines as the movement of the sheet to the right frees the point 23 for such movement. As the sheet emerges from the rolls 15 it falls upon the slide 30 and then passes under the influence of gravity underneath the alternator and above the next oncoming sheet over onto the slide 17 from which point it pursues the conventional course.

The succeeding sheet finds the alternator in the position indicated in dotted lines in Fig. 1 and the process is repeated except that this sheet is directed to the left and falls immediately upon the slide 17. It forces the alternator back to the position shown in solid lines in Fig. 1.

It will be observed that the sheets which will fall upon the slide 17 will have their list edges toward the right of the drawing, whereas the sheets which fall upon the slide 30 will have their list edges to the left of the drawing, and this relationship is carried through into the final stack.

It has been discovered that the speed of movement of the sheets from the slide 30 is sufficiently rapid that there is no interference with the normal and conventional feeding of the sheets from the machine.

The foregoing detailed description has been given for clearness of understanding only, and no unnecessary limitations should be understood therefrom.

What I claim as new, and desire to secure by Letters Patent, is:

1. In a feed device for metal sheets, means for feeding sheets seriatim in an upward path, a first slide directed downwardly from the upward path, a second slide directed upwardly from the upward path and so positioned and arranged that sheets dropping thereon are passed by gravity onto the first slide, and rock means in the path having a cam surface facing each slide and adapted alternately to guide one sheet to one slide and the succeeding sheet to the other slide, said

rock means being shaped and positioned so that each sheet contacting one of the cam surfaces thereof deflects the rock means to bring the other cam surface to the sheet engaging position.

2. A feed device for metal sheets, comprising, means for feeding sheets seriatim in an upward path, a slide directed downwardly from one side of said upward path, an upwardly directed slide immediately opposite the first mentioned slide so positioned and arranged that sheets dropping thereon are passed by gravity onto the first slide, and a triangular directing alternator pivotally mounted between the two slides, said alternator being constructed and arranged so that two adjacent generally upright sides alternately engage the sheets as they are fed upwardly in said path and each of said sides being shaped so that engagement of an upwardly moving sheet therewith gradually rocks the alternator to a position with

the other of said sides in said path, whereby said alternator directs succeeding sheets first to one of said slides and then to the other.

FRANK V. CARROLL.
